ATTORNEY

UNITED STATES PATENT OFFICE

MARIO ABRIANI, OF GENOA, ITALY

SHIP-UNLOADING DEVICE

Application filed July 30, 1927, Serial No. 209,485, and in Italy August 16, 1926.

The present invention refers to a ship unloading device of the greatest structural simplicity with the advantage of conveying merchandise very quickly, much quicker than 5 is usually done directly from the hold to the deck and by means of a chute directly from the deck to the quay or the lighters without using pulleys, cables and the like; moreover the device according to the invention 10 may be arranged as well within the air-hoses or ventilating-tubes or in the masts or supporting columns of booms without encumbering either hold or deck but occupying spaces hitherto not utilized.

15 Only by way of example the device is schematically illustrated in the accompanying drawings in which:

Fig. 1 shows a vertical section on the line 1—1 of Figure 2;

20 Fig. 2 shows a front view;

Fig. 3 is a section on line 2—2 of Fig. 1.

The device comprises a standard the uprights of which are formed of coupled channel irons, so that between them the car steering and traction pivots may glide, the ends 25 of the uprights being bent and conveniently shaped so as to guide the movement of the car pivots and cause the cars to take the horizontal position for loading, the inclined position for unloading, and the vertical one for 30 their descent into the hold.

As illustrated in Fig. 1 the uprights —a— and —b— have their middle part vertical and parallel while their lower and upper 35 ends show curves of a predetermined radius to oblige the end pivots —c— —d— to cause the cars to take in their rotation the different necessary positions for working.

The uprights —e— —f— are rectilinear 40 and parallel and act as guides for the central traction pivots —g— connected to endless chains —h— passing around wheels —i— and —l—. The upper wheels —i— are coaxial with driving wheels —m— which may 45 be acted upon by any motor and relative speed reducers. The lower wheels —l— are provided at the end of their axle with drums —n—. The cars —o— have fixed thereto pivots —e— —g— —d—, the pivots —c— and 50 —d— acting as guides and are slid able be-

tween uprights —a— and —b—. The pivots —g— are connected to the endless chains and move on the uprights —e— and —f—, these uprights being placed at a distance from one another coinciding with the diameter of 55 wheels —i— and —l—.

The terminal parts of all the uprights are diverging so that the various pivots may readily enter and move from the same.

The device is capable of being extended or 60 shortened according to the exigencies of the case by increasing or taking off a part of the uprights.

In the operation of the invention the carriages successively assume a substantially 65 horizontal position at the lower ends of the uprights *a* and *b*. While in this position the objects to be removed from the ship's hold are placed thereon and carried upwardly. As the carriages reach the upper ends of the 70 uprights they are caused to assume a substantially vertical position to dump the objects therefrom. When it is desired to load a ship the mechanism will be driven in a direction reverse to the arrow disclosed at the 75 upper end of Figure 1 to carry the objects downwardly.

Having now particularly described and ascertained the nature of said invention and in what manner the same is to be performed I 80 declare that what I claim is:

1. In connection with an air pipe in ships, a plurality of conveying plates moving up and down within said pipe, said plates being provided with end lugs and central lugs at 85 two opposite sides, funicular members pivotally connected to said central lugs, upper and lower wheels to guide and drive said funicular members, rectilinear guides tangent to said upper and lower wheels wherein slide 90 said central lugs, upright guides for the said end lugs, extending between the center levels of said wheels, outward circular and discontinued guide sections forming a continuation of one set of said upright guides and cooperating with the other set to swing the conveying plates to an inclined unloading position, rectilinear descending guides parallel to said upright guides cooperating with one set 95 of said tangent guides to keep the conveying 100 plates parallel to the horizontal.

plates in an inclined position while descending within said air pipes, curved guide sections joining one set of said upright guides from the center line of said upper wheels to the said rectilineal descending guides and cooperating with the said circular guide sections to swing the conveying plates to their inclined descending position, curved guide sections at the lower ends of the said rectilineal descending guides, curved guide sections at the lower ends of the said upright guides to receive the end lugs as left free by the said circular guide sections and said rectilineal descending guides, when the conveying plates have reached the hold and have taken their horizontal position.

2. In connection with air pipes in ships, an unloading elevator mounted in said pipe and comprising a plurality of elevating members, said elevating members being provided with end lugs and centrally disposed lugs on opposite side edges thereof, continuous funicular members to drive said elevating members up and down within said pipe, means disposed vertically within said pipe and coacting with the end lugs whereby said elevating members will be guided in a horizontal position while ascending, means carried within said pipe substantially adjacent said first-named means parallel thereto and coacting with the centrally disposed lugs whereby said elevating members will be guided in an inclined position while descending, and means carried at the lower end of said second-named means adapted to swing said elevating members into horizontal position before reascending.

3. In connection with air pipes in ships, an unloading elevator mounted in said pipe and comprising a plurality of conveying plates, continuous funicular members adapted to drive said conveyor plates up and down within said pipe, vertically disposed guide members carried within said pipe, said guide members being provided at their opposite ends with arcuately-shaped portions, pairs of vertical guides carried within said pipe and adapted to coact with said first-named guide members, said second-mentioned vertical guides being disposed substantially within the arcuately-shaped portions of said first-named guide members, and means carried at the lower ends of said guide members for horizontally disposing said conveyor plate at the termination of their descent.

In testimony whereof I have hereunto signed my name.

MARIO ABRIANI.
